ATTORNEY.

UNITED STATES PATENT OFFICE.

HUBERT LAWRENCE WHITE, OF UTICA, NEW YORK.

TELEPHONE-RECEIVER.

SPECIFICATION forming part of Letters Patent No. 683,631, dated October 1, 1901.

Application filed March 22, 1900. Serial No. 9,715. (No model.)

To all whom it may concern:

Be it known that I, HUBERT LAWRENCE WHITE, of Utica, in the county of Oneida and State of New York, have invented certain new 5 and useful Improvements in Telephone-Recievers; and I do hereby declare that the following is a full, clear, and exact description of the invention, which will enable others skilled in the art to which it appertains to make and 10 use the same, reference being had to the accompanying drawings, and to the figures of reference marked thereon, which form part of this specification.

The object of my present invention is to 15 provide a telephone receiving instrument which is economical in construction, has provision made for the nice adjustment of parts, and is free from the detrimental influence of heat and cold, causing contraction and 20 expansion of the parts, and more particularly the metal parts.

In the drawings, Figure 1 shows a vertical section of a telephone-receiver embodying the features of my invention. Fig. 2 shows the 25 cap of the receiver in section. Fig. 3 shows an edge view of the diaphragm removed from the receiver. Fig. 4 shows a vertical section of parts of the receiver, the inner parts shown being partially withdrawn from the casing, 30 which is also shown in section. Fig. 5 shows, partially in section and partially in side elevation, details of the construction. Fig. 6 shows a top or end view of the receiver with the cap and diaphragm removed. Fig. 7 35 shows a section taken on line E F of Fig. 1.

Referring to the reference-figures in a more particular description of the device, 1 indicates the permanent magnet. The permanent magnet is secured to a headpiece 4, the 40 ends of the arms of the magnet being received in recesses in the side of the head and secured to the head by screws 33, which also pass through and secure the electromagnet-cores 22, which are also received in the recesses in the sides of the head 4. The head 4 is externally screw-threaded, as indicated at 5, and is also recessed along opposite sides through the screw-threads to provide passages for the wires leading to the electromagnet-nets. The electromagnets are indicated by 50 66. The head 4 is screw-threaded into the

boss of the cup 7. The cup 7 is secured to the shell 8 by screw-threads (indicated by 9 on the external surface of the boss of the cup) engaging with internal threads on the shell 55 8. The shell and cup are provided with meeting shoulders, as indicated at 10, so that when the cup is screwed into the shell it comes to a firm and true bearing at the shoulders 10. The diaphragm is supported on the face end 60 of the cup 7 over the poles of the magnet and is secured in position by the cap 12, which is screw-threaded onto the end of the cup by screw-threads, (indicated by 13.) The cap 12 is provided with the usual opening 14 over 65 the center of the diaphragm. The portion of the shell 8 which incloses the cup 7 is arranged so that the walls of the shell do not touch the wall of the cup except at the shoulders 10. The arrangement of the parts is 70 such that the end of the shell next to the cap approaches the flanged edge of the cap so closely as not to leave an objectionable opening, but still remain out of contact, so that any expansion or contraction of the 75 shell or other parts will not injuriously affect the relative arrangement and adjustment of the parts. On the externally-screw-threaded head 4 there is also provided a lock ring or nut 15, which is adapted to be screwed 80 down onto the interior surface of the cup 7 and lock the cup and head 4 together when they are properly adjusted. To further secure the device in position after adjustment, and more particularly lock the ring 15, there 85 are provided set-screws 16, passing through the ring and adapted to engage on the inner surface of the cup.

The wires for the electromagnets are let down recesses in the sides of the head 4, as 90 before pointed out. The wires are indicated in the drawings by 17 and are attached to conductor-plates 18, mounted on an insulating-block 19 between the parts of the permanent magnet, and from the plates 18 extends 95 the cable, passing out of a suitable opening in the end of the shell.

The operation of the device is too well understood to warrant special description.

What I claim as new, and desire to secure 100 by Letters Patent, is—

1. In a telephone-receiver, the combination

- of the permanent and electro magnets mounted on the externally-screw-threaded head, a cup having an externally and internally screw-threaded boss receiving the said head, 5 a shell inclosing the cup and magnets, and screw-threaded onto the said boss of the cup and engaging against the base of the cup only, a diaphragm mounted on the edge of the cup and a flanged cap screw-threaded 10 onto the periphery of the cup, substantially as set forth.
2. In a telephone-receiver, the combination of a permanent horseshoe-magnet, an externally-screw-threaded head recessed from opposite sides through the screw-threads to receive the poles of the permanent magnet, electromagnets having pole-pieces also secured in said recesses of said head, a cup having an externally and internally screw-threaded boss, said boss receiving the said 15 head, a diaphragm mounted on the edges of said cup over said electromagnets, and a cap 20

securing said diaphragm in place, substantially as set forth.

3. In a telephone-receiver the combination 25 of an externally-screw-threaded head, a permanent and electro-magnets mounted on said head, a cap having an externally and internally screw-threaded boss, said boss receiving said head, grooves or recesses in the edge of 30 said head affording passage-ways for the electric conductors to the electromagnets, a diaphragm mounted on the edge of said cup over said electromagnets, a cap securing said diaphragm in place and a casing inclosing said 35 diaphragm and cup and screw-threaded onto said cup-boss, substantially as set forth.

In witness whereof I have affixed my signature, in presence of two witnesses, this 15th day of March, 1900.

HUBERT LAWRENCE WHITE.
